United States Patent

Des. 241,293
Patented Sept. 7, 1976

241,293

CABINET

Victorio Introini, Gallarate, Italy, assignor to Fratelli
Saporiti, Besnate, Varese, Italy

Filed Mar. 18, 1974, Ser. No. 452,413

Claims priority, application Italy Sept. 21, 1973

Term of patent 14 years

Int. Cl. D6—04

U.S. Cl. D6—165

FIG. 1.

FIG. 2.

FIG. 4.

FIG. 3.

FIG. 5.

FIG. 6.

FIG. 7.

FIG. 9.

FIG. 10.

FIG. 11.

FIG. 12.

FIG. 13.

FIG. 14.

FIG. 15.

FIG. 16.

FIG. 17.

FIG. 18.

FIG. 19.

FIG. 20.

FIG. 1 is a front, top and left side perspective view of a cabinet showing my new design;

FIG. 2 is a top plan view;

FIG. 3 is a front elevational view;

FIG. 4 is a left side elevational view;

FIG. 5 is a right side elevational view;

FIG. 6 is a rear elevational view;

FIG. 7 is a bottom plan view;

FIG. 8 is a front, top and right side perspective view of another embodiment of a cabinet showing my new design wherein two drawers which correspond to the vertical division of the FIG. 1 single drawer are included;

FIG. 9 is a top plan view thereof;

FIG. 10 is a left side elevational view thereof;

FIG. 11 is a front elevational view thereof;

FIG. 12 is a bottom plan view thereof;

FIG. 13 is a right side elevational view thereof;

FIG. 14 is a rear elevational view thereof;

FIG. 15 is another embodiment of a cabinet showing my new design wherein the cabinet is twice as wide as the FIGS. 1 and 8 cabinets and includes two drawers placed side by side and divided vertically like the FIG. 1 cabinet drawer;

FIG. 16 is a right side elevational view thereof;

FIG. 17 is a top plan view thereof;

FIG. 18 is a left side elevational view thereof;

FIG. 19 is a rear elevational view thereof; and

FIG. 20 is a bottom plan view thereof.

I claim:

The ornamental design for a cabinet, substantially as shown and described.
